UNITED STATES PATENT OFFICE.

ARTHUR G. BAKER AND FRANK W. KNOTT, OF DETROIT, MICHIGAN, ASSIGNEES TO
THE UNIVERSAL MACHINE COMPANY, OF DETROIT, MICHIGAN.

DISTRIBUTER FOR TYPE-SETTING MACHINES.

1,169,110.

Specification of Letters Patent. Patented Jan. 25, 1916.

Application filed August 20, 1910, Serial No. 578,079. Renewed June 21, 1915. Serial No. 35,427.

To all whom it may concern:

Be it known that we, ARTHUR G. BAKER and FRANK W. KNOTT, citizens of the United States, residing at the city of Detroit, county of Wayne, State of Michigan, have invented certain new and useful Improvements in Distributers for Type-Setting Machines, of which the following is a specification.

This invention relates to improvements in distributers for type-setting machines.

The objects of the invention are: First, to provide an improved electrical means for actuating a type-distributing carriage. Second, to provide an improved construction of carriage for carrying the dead matter to be distributed to the channels of a type-setting machine. Third, to provide an improved construction of type-setting machine wherein the type carriage, with the dead matter, can be readily returned over the mouths of the channels without undue friction on the type.

Further objects, and objects relating to structural details, will definitely appear from the detailed description to follow.

We accomplish the objects of our invention by the devices and means described in the following specification.

The invention is clearly defined and pointed out in the claims.

A structure which is a preferred embodiment of our invention is clearly illustrated in the accompanying drawing forming a part of this specification, in which:

Figure 1 is a front elevation view of our improved type-distributer in position on a type-setting machine, the rear ratchet bar 18 not being shown. Fig. 2 is an enlarged rear elevation of the same with a portion only of the frame track and ratchet bars illustrated. Fig. 3 is a plan view of the structure appearing in Fig. 2. Fig. 4 is a detail elevation view, partially in section, on a line corresponding to line 4-4 of Fig. 3, showing details of the wedge-bar, which elevates the type out of contact with the channels, and the related parts. Fig. 5 is an enlarged detail sectional view, taken on line 5-5 of Fig. 1, showing details of these same parts at that point. Fig. 6 is a detail view of one of the type 23, showing the nicks therein. Fig. 7 is an enlarged detail plan view of a portion of the tops or mouths of the channels, showing the wards

25 for engaging the nicks 24 of the type. Fig. 8 is a detail sectional view on a line corresponding to line 8-8 of Figs. 4 and 7, showing details of the channels in the carriage 3 and of the channels of the type-setting machine below. Fig. 9 is an enlarged detail sectional view of one of the channel walls, taken on a line corresponding to line 9-9 of Fig. 7, showing the slant of the upper end of the wards 25.

In the drawing, the sectional views are taken looking in the direction of the little arrows at the ends of the section lines, and similar numerals of reference refer to similar parts throughout the several views.

Considering the numerals of reference, the main frame 1 of the machine is provided with the usual type-channels 2 having suitable wards 25 having slanting tops for engaging the nicks 24 in the type 23. A top rail 4 is provided for the carriage 3 to travel upon, the rail being supported by suitable posts or supports 5-5. The posts 5-5 are secured to the top of the frame by bolts or cap-screws 6 and to the rail 4 by cap-screws or bolts 7. The carriage 3 is provided with carrying wheels 8, which are supported on the axle journal pins 9-9 on the cross arms 10. A guide wheel 11 engages the rear side of the rail 4, and is supported on vertical journal pins 12 on the bracket or arm 13, extending rearwardly from the carriage 3. A pair of guide wheels 14 is supported on vertical journal pins 15 in brackets 16 on the back side of the carriage 3. These guide wheels or rollers 14 contact with the flat back sides of the toothed ratchet bar 17, which toothed rack bar 17 with the rack bar 18 is secured to the posts 5 by suitable bolts or cap-screws 19. These rack bars 17 and 18 are provided with ratchet teeth 20 and 21, respectively, those teeth 20 on the bar 17 pointing toward the left of the machine and those 21 on the bar 18 pointing toward the right of the machine. These ratchet teeth coöperate with the pendulum and pawl devices for feeding and controlling the movements of the type carriage 3.

The type carriage 3 is provided with vertical channels 22 in which the dead matter or type 23 is placed for distribution. The carriage is advanced step-by-step over the channels 2 in a manner hereafter to be described. The type are provided with dis-

tinguishing nicks 24, which are engaged by suitable corresponding wards 25' on the sides of the channel type bars 25 in the usual way in distributors of this class. The 5 wards 25' are slightly beveled or slanted at their upper ends,—see Fig. 9,—to insure free passage of the type over the same. The tops of the channels are formed of bars 25, which rest in notches 62—63 in the sides of 10 the frame, and are retained by the removable bar 64, projecting into notches 65 in the ends of the bars 25.

15 A longitudinal rectangular groove 27 is cut in the under side of the carriage 3,—see Fig. 8,—and in this is fitted a longitudinal bar 26, which is wedge-shaped at its forward end 28, and is provided with a lateral stop-finger 29 at its rear or righthand end. A stop 30 is provided at the righthand end of 20 the frame 1 to contact with this stop finger 29, and a stop 31 is provided on the frame for engaging with the stop at that end of the movement of the bar 26. On the upper side 25 of this bar 26 are transverse notches 32 and 33 toward each end thereof, the same being V-shaped. A pawl 34, having a double beveled tooth 33' corresponding to and coacting with said V-shaped notches 32 and 33, is pivoted 30 between guide arms 36 on the righthand side of said carriage 3. This pawl 34 is urged downwardly by the spring 37, and urges the tooth 38 into yielding engagement with the notches 32 and 33 on the upper side 35 of the bar 26.

35 The carriage moves step-by-step from the lefthand side of the machine toward the right, the pawl 34, with its beveled tooth 33', engaging in the notch 33 toward the lefthand end of the bar 26. This carries the bar toward the right until the finger 29 contacts with the stop 30. The carriage then continues its travel toward the right step-by-step over the bar until the pawl 34, with its tooth 33', engages the notch 32. When the 40 carriage reaches this point, which is the end of its travel, the type 23 in the channels of the carriage will have been elevated up onto the bar 26, and, as the bar is now engaged by the said tooth, when the carriage is returned to the left, the bar will be carried with it until the finger 29 contacts with the stop 31. When the carriage has been moved to this position, the bar 26 will reach entirely 45 across the channel mouths. The continued movement of the carriage will pass the same off from the bar to the level space at the left of the machine. When the carriage reaches the extreme left in its movement, the pawl 34 will again engage by its beveled tooth 33' in the notch 33, and, as the carriage is advanced by the step-by-step movement toward the right, the bar will be carried in that direction until the finger 29 contacts with the stop 30, when the carriage will again move 50 onto the bar, repeating the evolution just re-

ferred to. It is thus clear that the type are raised out of contact with the channel mouths during the return of the carriage, and, consequently, the carriage is easily returned. 70

The carriage is advanced by the action of the double pawl 38 on the teeth 21 of the bar 18. The double pawl 38 is pivoted at 39 on the armature 40, which armature is pivoted at 41 on the back side of the carriage 3. 75 This armature is acted upon by the electromagnet 42, whereby the force of the magnet propels the carriage. The electric current is delivered to the magnet by the conductor 43, and passes from it at 61, or vice versa. 80 The pawls are urged into yielding contact with the rack bar by the spring 45. A stop pin 46 limits the downward movement of the pawls, and, by the action of the same on the cam surface 47, raises them out of engagement with the teeth 21 of the rack 18, except when the armature 40 is pulled by the magnet. A finger 52 is secured to the armature 40, and is urged upwardly by the spring 53,—see Fig. 4. The movement of the armature 40 in this direction is limited by the adjustable stops 48, secured to the back side of the carriage 3. 85

90 Double detent pawls 49 are pivoted at 50 on the back side of the carriage 3 and are 95 connected by a link 51 to the arm 52. These double pawls 49 are yieldingly associated together by the spring 49,—see Figs. 2, 3 and 4,—and it will be readily seen that, whenever the magnet 42 acts upon the armature 100 41, these detent pawls will be thrown downwardly and will engage the teeth 20 on the bar 17, and are timed so that the carriage will be advanced but a single step on each 105 impulse.

110 The contact of the magnet is controlled by the pendulum 54, which is pivoted by the rock shaft 55 in suitable journals on the top of the arm 13. The arm 56 is carried by this rock shaft 55 and is provided with a contact finger 57, which swings into contact with the contact button 58 on the spring 59. 115

120 The spring 59 is secured by the insulated binding post 60 to the arm 56, which is connected to the conductor 61, delivering current to or from the electromagnet 42. A light spring 62 connects the upper end of the link 51 to the spring 59, providing a yielding connection between these parts. The source of electric current may be a battery, as illustrated, or any other adequate supply.

125 From this description, it will be seen that, when the pendulum 54 swings, the contact finger 57 will swing into contact with the contact button 58. This closes the circuit and causes the electromagnet 42 to act. As there is a yielding spring contact between these parts, the contact is preserved for a sufficient time to insure the pull of the mag- 130

net on the armature 40. This, through the yielding contact, gives the pendulum an impulse by drawing the spring 59 down against the arm 56. The pendulum then swings to the right, and the contact between the finger 57 and the button 58 is broken, and the spring 53 causes the armature 40 to return to the normal position indicated in Fig. 4. When this pendulum movement occurs, however, and the magnets act, the pawls 39 engage the teeth 21 of the rack 18, which forces the carriage one step toward the right. Immediately after these teeth have engaged the teeth 21 of the rack 18, the detent pawls 49 are forced downwardly and engage the teeth 20 of the rack 17, which are pointed in the opposite direction, and the carriage is compelled to advance but a single step and there can be no overthrow. Also, this movement is very definite and brings the type exactly to the right point to fall into the channels beneath.

It will thus be seen that the carriage of the distributor is advanced very rapidly and very definitely by a very positive movement to exactly the right point for the distribution of the type. This is of very great importance. At the same time, it will be observed that, owing to the other parts of the distributor, the type can be very readily returned to the initial position without being compelled to pass over and in contact with the channel mouths. This makes the distributor very effective and insures proper distribution of the type, without danger of breakage and it insures the smooth operation of the entire device, so far as type distribution is concerned.

The method of elevating and protecting the type from engagement with the mouths of the type channels is important, and it can be made use of with various means of advancing and returning the carriage. Also, the particular electric means which we have shown for propelling our carriage could be made use of with any style of carriage. Our improved means of supporting the carriage on its rail might be made use of with any carriage.

We mention these facts, because we consider each of these features important, but, however, they lend themselves particularly well to each other. It is necessary that the carriage be advanced with strong force, and definitely in order to advance it onto the wedge-shaped bar, and the particular way in which we support the carriage prevents friction of rubbing between the parts and insures the full action of the propelling device.

Many variations, no doubt, will suggest themselves to those skilled in the art to which our invention pertains. We have shown the form in which we prefer it. We

desire to claim the same specifically and also broadly.

Having thus described our invention, what we claim as new and desire to secure by Letters Patent is:—

1. In a type distributor for typesetting machines, the combination of the frame of the machine with suitable type channels with open mouths at their upper ends; a carriage rail; a suitable carriage with vertical channels for the type to be distributed, the said carriage having suitable carrying and guide wheels for supporting the same on said rail; a wedge-shaped longitudinal bar arranged on the top of the said type channels, within a suitable longitudinal groove in the bottoms of the type channels of the said carriage, the same having V-shaped notches; suitable stops for limiting the movement of the said wedge-shaped bar; a pawl with a double beveled tooth to engage said V-shaped notches in said bar, whereby the bar will be yieldingly engaged and retained under the carriage during the return thereof over the mouths of the type channels and which will be moved away from over said channels by the advance of the carriage; ratchet toothed rack bars on the top of the frame of the said type setting machine with teeth pointing in opposite directions; actuating pawl means for engaging one of the said rack bars for advancing the carriage; detent pawls pivoted to said carriage to engage the opposite ratchet rack bar and limit the advance of said carriage; a suitable armature pivoted on the said carriage and carrying said actuating pawl means; an electromagnet for acting on the said armature; a suitable source of electric supply with an open circuit leading to said magnet; a finger secured to the said armature; a link connection therefrom to the detent pawls to throw the same into engagement with said ratchet rack bar when the carriage is advanced; a pendulum means; a spring carried by the said pendulum means suitably insulated therefrom and having a contact point thereon; a spring connection from said spring to the armature; and a contact finger actuated by the said pendulum and moving into yielding contact with the said contact point, whereby the pendulum, when swinging in one direction, will close the circuit, and will be actuated in the opposite direction by the impulse of the magnet, whereby the interval of operation of the said apparatus is controlled, all co-acting substantially as described and for the purpose specified.

2. In a type distributor for typesetting machines, the combination of the frame of the machine with suitable type channels with open mouths at their upper ends; a carriage rail; a suitable carriage with vertical channels for the type to be distributed suitably

guided above said channels; a wedge-shaped longitudinal bar arranged on the top of the said type channels, within a suitable longitudinal groove in the bottoms of the type channels of the said carriage, the same having V-shaped notches; suitable stops for limiting the movement of the said wedge-shaped bar; a pawl with a double beveled tooth to engage said V-shaped notches in said bar, whereby the bar will be yieldingly engaged and retained under the carriage during the return thereof over the mouths of the type channels and which will be moved away from over said channels by the advance of the carriage; and means for advancing said carriage step-by-step, all coacting substantially as described and for the purpose specified.

3. In a type distributor for typesetting machines, the combination of the frame of the machine with suitable type channels with open mouths at their upper ends; a suitable carriage with vertical channels for the type to be distributed, suitably guided above said channels; a wedge-shaped longitudinal bar arranged on the top of said type channels within a suitable longitudinal groove in the bottoms of the type channels of the said carriage, the same having V-shaped notches; suitable stops for limiting the movement of the said wedge-shaped bar; a pawl with a double beveled tooth to engage said V-shaped notches in said bar, whereby the bar will be yieldingly engaged and retained under the carriage during the return thereof over the mouths of the type channels, and which will be moved away from over said channels by the advance of the carriage; and means for advancing said carriage step-by-step, all coacting substantially as described and for the purpose specified.

4. In a type distributor for typesetting machines, the combination of the frame of the machine with suitable type channels with open mouths at their upper ends; a suitable carriage with vertical channels for the type to be distributed suitably guided above said channels; a wedge-shaped longitudinal bar arranged on the top of the said type channels; suitable stops for limiting the movement of the said wedge-shaped bar; means carried by said carriage to yieldingly engage said bar, whereby the bar will be yieldingly engaged and retained under the carriage during the return thereof over the mouths of the type channels and which will be moved away from over said channels by the advance of the carriage; and means for advancing said carriage step-by-step, all coacting substantially as described and for the purpose specified.

5. In a type distributor for typesetting machines, the combination of the frame of the machine with suitable type channels

with open mouths at their upper end; a suitable carriage with vertical channels for the type to be distributed guided above said channels; a pair of ratchet toothed rack bars on the top of the frame of the said type setting machine with teeth pointing in opposite directions; actuating pawl means for engaging one of the said rack bars for advancing the carriage; detent pawls pivoted to said carriage to engage the opposite ratchet rack bar and limit the advance of said carriage; a suitable armature pivoted on the said carriage and carrying said actuating pawl means; an electromagnet for acting on the said armature; a suitable source of electric supply with an open circuit leading to said magnet; a finger secured to the said armature; a link connection therefrom to the detent pawls to throw the same into engagement with said ratchet rack bar when the carriage is advanced; a pendulum means; a spring carried by the said pendulum insulated therefrom by a suitable binding post and having a contact point thereon; a spring connection from said spring to the armature; and a contact finger actuated by the said pendulum and moving into yielding contact with the said contact point, whereby the pendulum, when swinging in one direction, will close the circuit, and will be actuated in the opposite direction by the impulse of the magnet, whereby the interval of operation of the said apparatus is controlled, all coacting substantially as described and for the purpose specified.

6. In a type distributor for typesetting machines, the combination of the frame of the machine with suitable type channels with open mouths at their upper end; a suitable carriage with vertical channels for the type to be distributed guided above said channels; a pair of ratchet toothed rack bars on the top of the frame of the said type setting machine with teeth pointing in opposite directions; actuating pawl means for engaging one of the said rack bars for advancing the carriage; a suitable armature pivoted on the said carriage and carrying said actuating pawl means; an electromagnet for acting on the said armature; a suitable source of electric supply with an open circuit leading to said magnet; a finger secured to the said armature; a pendulum means; a spring carried by the said pendulum insulated therefrom by a suitable binding post and having a contact point thereon; a spring connection from said spring to the armature; and a contact finger actuated by the said pendulum and moving into yielding contact with the said contact point, whereby the pendulum, when swinging in one direction, will close the circuit, and will be actuated in the opposite direction by the impulse of the magnet, whereby the interval 125 130

of operation of the said apparatus is controlled, all coacting substantially as described and for the purpose specified.

7. In a type distributor for typesetting machines, the combination of the frame of the machine with suitable type channels with open mouths at their upper end; a suitable carriage with vertical channels for the type to be distributed guided above said channels; ratchet means to advance said carriage step-by-step; a suitable armature carrying said actuating ratchet means; an electromagnet for acting on the said armature; a suitable source of electric supply with an open circuit leading to said magnet; a finger secured to the said armature; a pendulum means; a spring carried by the said pendulum insulated therefrom by a suitable binding post and having a contact point thereon; a spring connection from said spring to the armature; and a contact finger actuated by the said pendulum and moving into yielding contact with the said contact point, whereby the pendulum, when swinging in one direction, will close the circuit, and will be actuated in the opposite direction by the impulse of the magnet, whereby the interval of operation of the said apparatus is controlled, all coacting substantially as described and for the purpose specified.

8. In a type distributor for typesetting machines, the combination of the frame of the machine with suitable type channels with open mouths at their upper ends; a suitable carriage with vertical channels for the type to be distributed guided above said channels; pawl and ratchet means for advancing the said carriage; a pendulum supported by the said carriage; the pawls of said pawl and ratchet means connected to be actuated by the said pendulum; an electromagnet; and means actuated by said pendulum for closing the circuit to the said magnet for giving impulse to the said pendulum, coacting for the purpose specified.

9. In a type distributor for typesetting machines, the combination of the frame of the machine with suitable type channels with open mouths at their upper ends; a suitable reciprocating carriage with vertical channels for the type to be distributed guided above said channel; a bar to retain the type in elevated position during the return of the carriage and type over the channel mouths; and means for withdrawing the

bar longitudinally to permit the distribution of the type and the operation of the said carriage, as specified.

10. In a distributor for typesetting machines, the combination of the frame of the machine with suitable type channels with open mouths at their upper ends; a carriage rail; a suitable carriage with vertical channels for the type to be distributed, the said carriage having suitable carrying wheels to travel on the said rail and horizontal guide wheels for engaging the sides of the said rail, whereby the said carriage is supported above the said channel mouths; and means for advancing the carriage step-by-step for the distribution of the type, coacting as specified.

11. In a type distributor for typesetting machines, the combination of the frame of the machine with suitable type channels with open mouths at their upper ends; a suitable reciprocating carriage with suitable channels for the type to be distributed guided above said channels; opposite facing ratchet-toothed rack bars facing in opposite directions, supported on one of the said parts; an actuating pawl for engaging one of the said rack bars; a detent pawl for engaging the opposed rack bar; means for actuating the said pawls, connected and timed, whereby, on the advance of the carriage, the detent pawl will be thrown into engagement to limit and define the step-by-step movement; and suitable means for giving impulse to the said ratchet means, coacting for the purpose specified.

12. In a type distributor for a type-setting machine, the combination of the frame of the machine, with suitable type channels, the partitions between said type channels being provided with wards with slanted upper ends; a suitable reciprocating carriage with suitable channels for the type to be distributed, guided above said channels; and means for raising the type out of contact with the tops of the said channels to permit the return of the carriage, coacting for the purpose specified.

In witness whereof, we have hereunto set our hands and seals in the presence of two witnesses.
